(57) **CLAIM**

The ornamental design for an electric pump head, as shown and described.

DESCRIPTION

FIG. 1 is a perspective view of the electric pump head showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a partial enlarged view of portion 9 in FIG. 1; and,

FIG. 10 is a partial enlarged view of portion 10 in FIG. 2.

The broken lines depict portions of the electric pump head that form no part of the claimed design. The dot-dash broken lines encircling portions of the claimed design that are illustrated in enlargements form no part of the claimed design.
